OK D 12,073

No. 12,073

DECEMBER 21, 1880

UNITED STATES PATENT OFFICE.

ORVILLE S. HARMON, OF BROOKLYN, NEW YORK, ASSIGNOR TO P. LORIL-LARD & CO., OF JERSEY CITY, NEW JERSEY.

DESIGN FOR A TOBACCO-CUTTER.

SPECIFICATION forming part of Design No. 12,073, dated December 21, 1880.

Application filed August 18, 1880. Term of patent 3½ years.

To all whom it may concern:

Be it known that I, ORVILLE S. HARMON, a citizen of the United States, residing in the city of Brooklyn, county of Kings, and State 5 of New York, have invented and produced a new and original Design for Tobacco-Cutters, of which the following is a description.

It is the object of this invention to give to this article of manufacture, which in use commonly stands exposed to view upon a counter or table, much beauty of outline and artistic finish by making its principal parts of such shape and configuration as will constitute it a 10 thing of ornamental beauty without impairing its utility as a machine.

To this end the base-plate that supports the working parts is given a form, shape, or configuration approximating to that of an alligator, while the lever or handle by which the 15 movements of the knife or cutter are produced is given a form, shape, or configuration approximating to that of a snake, and these features constitute the essential elements of the design. Said shapes or configurations may 20 depend wholly upon their contour or outlines,

or the representation may be made more effective by engraving, carving, and the like, whereby the surface, form, or shape of the skin of the alligator and snake are imitated; and the effect may or not be heightened by 30 coloring in any approved manner.

What I claim is—

1. The design for the bed-plate of a tobacco-cutter, as shown and described, the essential feature of which is the shape or configuration 35 approximating in outline or contour to that of an alligator.

2. The design for the handle of a tobacco-cutter, as shown and described, the essential feature of which is the shape or configuration 40 approximating in outline or contour to that of a snake.

In testimony whereof I have hereunto set my hand in the presence of two subscribing witnesses.

ORVILLE S. HARMON.

Witnesses:

T. H. PALMER,
H. T. MUNSON.
